Primary Examiner — Darlington Ly*Assistant Examiner* — Jeremy Koenig(74) *Attorney, Agent, or Firm* — Joseph A. Andelin; Fish IP Law, LLP(57) **CLAIM**

The ornamental design for a wheel rim as shown and described.

DESCRIPTION

FIG. 1 is a front elevation view of a wheel rim embodying the new design;

FIG. 2 is a top, front, and right-side perspective view thereof; and,

FIG. 3 is a cross-sectional view thereof.

The dash dash broken lines depict portions of the wheel rim that form no part of the claimed design. The dash dot dash broken lines depict boundary lines that form no part of the claimed design.

1 Claim, 3 Drawing Sheets(56)
